UNITED STATES PATENT OFFICE

2,539,809

MATERIAL STORAGE RACK

Daniel J. Buckley, Canton, Mass.

Application August 23, 1946, Serial No. 692,573

6 Claims. (Cl. 214—10.5)

1

This invention relates to a storage rack and has for its primary object to support stock piles of elongated material in spaced relation to a floor, and from one another.

A further object is to accommodate stock piles of different dimensions, and to allow the stakes which separate the stock piles from one another to be moved in accordance with the size of the stock pile.

The above and other objects may be attained by employing this invention which embodies among its features a pair of beams adapted to rest in spaced parallel relation on the floor, of a storage building, each beam comprising spaced parallel channel members with their flanges disposed outwardly and spacers secured to the webs of the channel members to form longitudinally spaced sockets, and stakes detachably fitted into the sockets to separate one stock pile from another and to support the sides of the stock piles.

In the drawings,

Figure 1 is a perspective view of a material rack embodying the features of this invention showing a stock pile supported therein,

Figure 2 is a fragmentary perspective view of one of the beams, and illustrating a modified form of stake holding socket,

Figure 3 is a fragmentary perspective view similar to Figure 2 of a further modification, and

Figure 4 is a transverse sectional view through one of the beams illustrated in Figure 1.

Referring to the drawings in detail, my improved material rack comprises a pair of spaced parallel beams each designated generally 10 and comprising spaced parallel channel members 11 the flanges 12 of which are disposed outwardly as will be readily understood upon reference to the drawings. In the preferred form of the invention the webs of the channel members are provided with rows of longitudinally spaced apertures 13 the purpose of which will be more fully hereinafter explained.

A transversely extending spacer 14 extends between the spaced channel members in alignment with each pair of openings 13 formed therein, and these spacers 14 are secured in proper position between the channels 11 by forming through the openings 13 welding plugs 15. As illustrated in Figure 1, the spacers 14 are spaced from one another a distance substantially equal to the distance between the webs of the channel members 11 of each beam 10 so as to form a longitudinal row of spaced sockets in which the lower ends of stakes 16 are adapted to be received. In the embodiment illustrated in Figure 1, the stakes

2

15 comprises I-beam sections which may be fitted into the sockets, and form spacers which separate one stock pile from another and also support the sides of the stock piles against collapse.

5 In the modification illustrated in Figure 2, each beam designated generally 17 comprises a pair of spaced channel members 18 the flanges 19 of which are turned outwardly as previously described. Instead of the flat plate spacers previously used I employ tubular spacers 20 which are arranged in a single longitudinal row between the webs of the channel members 18 and these spacers are welded at diametrically opposite points to one another and to the webs of the channel members 18. It will thus be seen that a plurality of longitudinally spaced tubular sockets 21 are formed in which tubular stakes 22 which may take the form of a standard pipe are received. Obviously, the stakes may be moved to different positions longitudinally of the beam 17 so as to accommodate stock piles of different sizes.

25 In the modification illustrated in Figure 3, a beam designated generally 23 like those previously described comprises a pair of channel members 24 arranged in spaced parallel relation with the flanges 25 thereof disposed outwardly, but instead of the spacers previously described, I employ spacers 26 each of which comprises a short section of an I-beam the flanges 27 of which are welded at their ends to opposite webs of the channels 24 in order to form spaced sockets 28 for the reception of stakes, similar to the stakes 16, above described.

35 In operation, it will be understood that the stakes are set in their respective sockets of the beams 10, a distance from one another sufficient to accommodate the stock pile of material to be supported. Obviously, as the pile decreases in size the stakes may be moved closer together in order properly to support the stock piles, and keep a plurality of piles occupying the rack separated from one another.

40 While in the foregoing there has been shown and described the preferred embodiment of this invention it is to be understood that minor changes in the details of construction, combination and arrangement of parts may be resorted to without departing from the spirit and scope of the invention as claimed.

50 I claim:

1. A storage rack adapted to support stock piles of elongated material in spaced relation to a floor which includes a pair of beams adapted to rest in spaced parallel relation on the floor, each beam comprising spaced parallel channel mem-

bers with their flanges disposed outwardly and spacers secured to the webs of the channel members to form longitudinally spaced sockets, and stakes detachably fitted into the sockets to separate one stock pile from another and to support the sides of the stock piles.

2. A storage rack adapted to support stock piles of elongated material in spaced relation to a floor which includes a pair of beams adapted to rest in spaced parallel relation on the floor, each beam comprising spaced parallel channel members with their flanges disposed outwardly, and a longitudinal row of tubular spacers welded to one another and to the webs to form longitudinally spaced sockets, and stakes detachably fitted in said sockets to separate one stock pile from another and to support the sides of the stock piles.

3. A storage rack adapted to support stock piles of elongated material in spaced relation to a floor which includes a pair of beams adapted to rest in spaced parallel relation on the floor, each beam comprising spaced parallel channel members with their flanges disposed outwardly, and short lengths of longitudinally spaced I-beam stock, the flanges of which are welded to the webs of the channel member to form longitudinally spaced sockets and stakes detachably fitted into the sockets to separate one stock pile from another and to support the sides of the stock piles.

4. A storage rack adapted to support stock piles of elongated material in spaced relation to a floor which includes a pair of beams adapted to rest in spaced parallel relation on the floor, each beam

comprising spaced parallel channel members with their flanges disposed outwardly and spacers secured to the webs of the channel members to form longitudinally spaced sockets.

5. A storage rack adapted to support stock piles of elongated material in spaced relation to a floor which includes a pair of beams adapted to rest in spaced parallel relation on the floor, each beam comprising spaced parallel channel members with their flanges disposed outwardly, and a longitudinal row of tubular spacers welded to one another and to the webs to form longitudinally spaced sockets.

6. A storage rack adapted to support stock piles of elongated material in spaced relation to a floor which includes a pair of beams adapted to rest in spaced parallel channel members with their flanges disposed outwardly, and short lengths of longitudinally spaced I-beam stock, the flanges of which are welded to the webs of the channel member to form longitudinally spaced sockets.
